HYDRAULIC TORQUE WRENCH

William J. Bortle, Wireton, Pa., and Charles E. Ranshaw, Wilmington, Del.

Application March 10, 1948, Serial No. 14,133

3 Claims. (Cl. 81—52.4)

1

This invention appertains to novel and useful improvements in tools, particularly adapted for use in applying torque to a work piece.

An object of this invention is to apply a predetermined torque to a screw, lug, bolt or the like.

Another object of this invention is to hydraulically maintain the work engaging handle in a selected position until a predetermined torque is applied.

Another object of this invention is to selectively regulate the amount of torque which might be applied to a work piece, then permit the handle to move harmlessly.

Another object of this invention is to engage the work by an arm, then urge the arm by means of a rod, the urging being transmitted on a piston in a hydraulic cylinder, resistance being supplied against the movement of the piston until a predetermined force is supplied to the piston, at which time the force will override the urging of the piston.

Another object of this invention is to provide a simplified device which permits only a predetermined torque to be applied on a nut, bolt, lug or the like.

Other objects and features of novelty will become apparent to those skilled in the art, in following the description of the preferred forms of the invention, illustrated in the accompanying drawings, wherein:

Figure 1 is an elevational side view of one form of the invention;

Figure 2 is a plan view of the invention shown in Figure 1, showing the same utilized in association with a conventional work engaging tool;

Figure 3 is a bottom view of the invention illustrated in Figure 2;

Figure 4 is an end view of the invention illustrated in Figure 2;

Figure 5 is a sectional view taken substantially on the line 5—5 of Figure 4 and in the direction of the arrows;

Figure 6 is a transverse sectional view of the invention shown in Figure 3, taken substantially on the line 6—6 of Figure 5 thereof and in the direction of the arrows;

Figure 7 is a perspective view of a selected element of the invention, portions being removed to illustrate details of construction;

Figure 8 is a perspective view of the handle 50 for use in association with the details shown in Figure 7;

Figure 9 is a side elevational view of the second form of the invention, portions being broken away to illustrate details of construction;

2

Figure 10 is a plan view of the invention illustrated in Figure 9;

Figure 11 is a side elevational view of a portion of the second form of the invention, portions being shown in section to illustrate details of construction, and;

Figure 12 is a transverse sectional view taken substantially on the line 12—12 of Figure 11 and in the direction of the arrows.

This invention has been developed to provide a device for applying a predetermined torque to a screw, lug, bolt or any other element which is to be turned either for fastening or unfastening purposes. As is well known certain bolts and nuts should receive a predetermined amount of torque in order to fasten them properly. One example of such a construction is in association with internal combustion engines, wherein the head bolts are to be applied with such force as to maintain them tightly, however, if too much force is applied they will invariably break.

It is one of the prime purposes of the invention to provide a practical device of the nature described which may be easily carried or transported.

The general operation of the invention is as follows: A housing is provided which has a bore therein and a piston slidably received in the bore. The piston may either directly communicate with an orifice provided in a partition within the bore or an alternate means may be utilized in association with such a construction. However, the piston is hydraulically communicated with any suitable fluid within the piston and this fluid is trapped within one zone, on one side of the said partition. By regulating the compressive force of a spring urging the piston in the orifice and by engaging the work piece by means of a pivoted arm associated with the housing, a predetermined force may be applied to the work piece by turning the housing and having an element of the pivoted arm engage the piston either directly or indirectly in order to overcome the spring tension of the compressor spring. Until the tension is overcome, the force exerted on the housing or handle will turn the nut, screw or the like. However, when this spring tension is overcome the handle will simply turn forcing the plunger in and not affecting the work piece.

Means for regulating the tension of the said spring urging the piston is provided, whereby selective amounts of torque may be applied to the work piece in accordance with the exigencies of the job at hand and in accordance with the desire of the operator of the invention.

Referring now to the specific structure of the first embodiment of the invention, attention is directed to Figures 1-8 inclusive. A housing 10 is provided with a partition 12 extending across the bore 14 thereof. This housing also has an extension 16 either integral or welded thereto for a purpose to be described subsequently.

In this form of the invention a handle 18 is provided with bifurcations 20 and 22 respectively at one end thereof and an aperture extending through the said bifurcations. A pivot pin of conventional description is adapted to be positioned in the aligned apertures and in a suitable aperture 24 formed in the angular portion or link 26 projecting from the said extension 16. By this construction, it is apparent that the handle is pivotally associated with the housing 10.

A sleeve type insert 28 is supplied in the said housing 10 and has a plunger or piston 30 reciprocatively received therein. This plunger is resiliently biased by means of a spring 32 which seats on one end of the said piston 30 and within a suitable cup-like element 34, secured to the base of the housing within the bore 14 thereof. A suitable lug or protuberance 36 may be formed integral with the said piston 30 in order to maintain the spring 32 in a fixed position relative to lateral movement within the said bore 14.

The said handle 18 is provided with a protuberance 38 formed integral therewith, which protuberance engages the exterior end of the said piston 30. A suitable aperture or the like may be supplied through the end of the extension 16 and the continuation 26 thereof. In this aperture there may be fitted the conventional rectangular socket maintaining lug 40. If it is found desirable this socket maintaining lug may be secured permanently to these elements 16 and 26 or, may be formed integral therewith. This is but a matter of choice of construction.

A conventional socket may be fitted over the lug or pin 40 for engaging a conventional nut, bolt or the like. The pivoted handle 18 may then be actuated, the protuberance 38 seating on the terminal of the piston 30. As the handle is moved, the conventional nut is turned however, when the resistance of the nut is of such proportions that the resistance through turning of the piston is overcome, the handle 18 will urge the piston 30 downwardly against the force of the spring 32 and the indication of the proper amount of torque is completed and effected.

Means for supplying resistance to movement of the piston 30 is provided. The means illustrated in the first form of the invention is seen best in Figure 5 wherein a plunger or rod 44 is slidably received in a suitable boss 46 formed integral with the end of the housing 10. The said boss 46 may be externally threaded in order to adjustably accommodate a cap or closure 48. Further, a spring 50 is seated in the cap 48 and bears against one end of the said rod 44. By manipulating the said cap 48 the compression of the spring 50 may be regulated and of course, suitable indicia might be placed on the said cap 48 as calibrated in accordance with the inherent resiliency of the spring.

The opposite end of the said rod 44 seats in a suitable orifice formed in the said partition 12. As the fluid in the housing 10 is compressed by means of the movement of the piston 30, it is forced toward the said orifice 52 and against the terminal portion of the said rod 44. When this force reaches a predetermined value the spring 50 will compress permitting the fluid to rush from

one side of the partition to the other and allowing the piston to react against the resiliency of the spring 32, which is used for piston return purposes.

While the spring 32 is returning the said piston 30, a suction is created within the housing, drawing the fluid within the chamber disposed on the opposite side of the partition 12, through a check valve generally indicated at 54. The preferable form of the check valve consists of a removable insert 56 which is threadedly received in the said partition 12. A valve plug or plunger 58 is received in the insert and cooperates with a suitable orifice formed in the said partition 12. A spring 60 seats against a detachable end plate 62 of the said insert 56 and against the said valve plunger or plug 58. This of course maintains the plug or plunger 58 in the closing position at all times until reacted on by means of the movement of the piston 30 in the direction normally urged by the said spring 32.

Referring now to the second form of the invention, attention is directed primarily to Figures 9-12. Here, a housing 70 is supplied with a bore 72 at one end thereof and a recess 74 aligned therewith. An extension 76 is pivotally associated with the said housing 70 through the medium of the pin 78 which is offset relative to the longitudinal axis of both the housing 70 and the said extension 76. The above described work engaging lugs 40 may be used in association with one terminal portion of the said extension 76, if found desirable.

A rod 80 is threadedly received in a suitable central bore formed in the housing 70 and extends through a handle-like formation 82 formed integral with the said housing and forming a portion thereof. A suitable indicia bearing knob 84 may be supplied on one terminal portion of the said rod 80 and a cap or cage 88 may be secured to the opposite end of the said rod. For assembly purposes the said cage may be attached by means of a suitable screw 90 and, resilient biasing means, preferably the spring 92 is seated in the said cap.

The opposite end of the said spring 92 rests in a bore 94 formed at one end of a spring loaded piston 96. This piston or valve is slidably received in the said bore 72 and communicates with an aperture 98 formed in the partition 100. Of course, the partition separates the bore 72 into separate compartments and if it is found desirable, sleeves 102 and 104 respectively may be supplied in each side of the bore 72.

A centrally apertured closure cap 106 may be supplied at one end of the said bore 72 by means of a threaded connection. And, a plunger or piston 108 is slidably received through the said apertured cap or closure 106 and in the said sleeve 104. Hydraulic fluid may be supplied in the said bore to be communicated back and forth through the orifice 98.

The operation of this form of the invention is very similar to the operation of the aforementioned embodiment however, it will be noted that the offset pivot 78 permits both elements 76 and the housing 70 to be axially aligned and further, the said elements 76 and 70 may be folded relative to each other for transportation purposes.

When the predetermined force is applied to the piston 108, the fluid in the bore 72 rushes through the orifice 98, urging the piston 96 against the compressive force of the spring 92. This permits the fluid to flow through the orifice and permits the housing 70 and extension 76 to be mutually pivoted. The compression in the spring

92 is regulated by adjustment of the rod 80
threadedly in the said housing and handle.

While there has been described and illustrated
but preferred forms of the invention, it is ap-
parent that certain variations may be made with-
out departing from the spirit thereof. Accord-
ingly, limitation is sought only in accordance with
the scope of the following claims.

Having described the invention, what is claimed
as new is:

1. A regulatable torque application wrench
comprising a housing having a bore, a piston in
the bore, resilient means for biasing said piston,
a wall having an orifice for seating said piston,
controllable means for compressing said resilient
biasing means, an arm pivoted to said housing,
a plunger slidably received in said housing and
engaging said arm, work engaging means associ-
ated with said arm, said resilient biasing means
comprising a spring seated on said piston, said
compressing means comprising an axially ad-
justable rod coaxially disposed with respect to
said plunger and carried by said housing and
having said spring seated thereon.

2. A regulatable torque application wrench
comprising a housing having a bore, a piston in
the bore, resilient means for biasing said piston,
a wall having an orifice for seating said piston,
controllable means for compressing said resilient
biasing means, an arm pivoted to said housing and
forming a longitudinal extension thereof, a plunger
slidably received in said housing and engag-

ing said arm, work engaging means associated
with said arm, said arm having its pivot offset
from the longitudinal axis of said housing and
said housing and said arm being axially aligned
when in operation.

5 3. The combination of claim 1 and said arm
being pivoted to said housing by means of a
mounting element fixed to and extending from
said housing, a link, a pin adapted to hold a
standard socket, said pin connecting one end of
10 said link with the outer end of said mounting ele-
ment and arranged to be rotated by said link, and
said arm being connected to the end of said arm
opposite from the end connected with said mount-
ing element.

WILLIAM J. BORTLE.
CHARLES E. RANSHAW.
